UNITED STATES PATENT OFFICE.

JOSEPH PHILLIPS, OF MIDLAND, ONTARIO, CANADA.

LOCK.

No. 884,414.

Specification of Letters Patent.

Patented April 14, 1908.

Application filed July 1, 1907. Serial No. 381,726.

To all whom it may concern:

Be it known that I, JOSEPH PHILLIPS, a subject of the King of Great Britain and Ireland, and a resident of Midland, in the county 5 of Simcoe, Province of Ontario, and Dominion of Canada, gunsmith, have invented a new and Improved Lock, of which the following is a specification.

My invention relates to locks for doors, 10 and the objects of my improvements are,— to provide a lock that may be operated by either a thumb latch or by a knob latch, or be arranged to be operated by both or either at will; to provide a lock, the bolt of which 15 shall be slidable by one key while the admission of the key be determined by one or a plurality of keys; and to provide a lock of this type with interior shields which shall prevent the entrance of all instruments such 20 as skeleton keys and lock picks. I attain these objects by the construction illustrated in the accompanying drawings, in which—

Figure 1 is a view of the interior of the lock with the face plate removed. Fig. 2 is a 25 cross section on an enlarged scale taken on the line A—A of Fig. 1. Fig. 3 is a side view of the lock. Fig. 4 is an end view of the same.

Similar reference characters refer to like 30 parts throughout the several views.

The lock shown is composed of the case 3, to which the cover 4 is attached by means of the screws 5. When it is desired to use the lock as a side lock for either right or left 35 hand doors, screws may be inserted through the holes 6. When the lock is to be used as a mortise lock, the face plate 7 is attached, which has two lips 8 that fit the top and bottom of the lock and are secured thereto by 40 screws 9. Holes 10 provide for screws that are to hold the face plate to the edge of the door.

The latch portion of the lock will be described first, being distinct in its operation 45 from the locking part.

The knobs 12 are provided with recesses into which the lugs 13 on the ends of the hubs 14 engage. Into these hubs a tube 15, having a slot, engages, and on the tube are 50 mounted the cam 16, the spacing rings 17, and through it passes the bolt 13 which engages the nut 19 at the outer face of one of the knobs. This construction is very strong, there being no small screws to be 55 lost and all the stress coming on the strong tube 15. The knobs may be of any desired

material, and the space between the hubs may be regulated by the number and length of the rings 17.

The cam 16 is shown in Fig. 1, from which 60 it will be seen that it will slide back the latch 20 when turned in either direction. The end 21 of the latch is beveled in the usual manner, and its body is in the form of a flat plate having a slot 22 for the hub 23 of the 65 cam, and its inner end has a raised portion 24 which engages the cam 16. As this raised portion is on one side only, the latch can be turned over so that it will be adapted for either right or left hand doors.

The widened portion 24 of the latch is provided with recesses 25 at its upper and lower edges into which the rounded end of the short arm 26 of the bell crank lever 27 engages, according to the way the latch is 70 turned. The free end of this lever is weighted and normally tends to hold the latch outward, but for quickness of movement the spring 28 may be added to assist the weight. The pivot 29 of this lever is secured in the 75 back 3.

Passing through a slot in the upper part of the lock is a lift link to the upper end of which may be attached the mechanism of a thumb-latch or any desirable connection by which, 80 especially when comprising a flexible connection, the latch can be withdrawn by a person at a distance. The lifter is in two parts, 30 and 31, the former provided with a slot to receive the hook 32 on the lever 27, the other 90 having the ring 33, the two parts being slidably connected by the pins 34 and slot 35 so that the parts may be entirely contained within the lock when it is to be used as a mortise lock. The lifter is guided between 95 pairs of pins 36 projecting from the cover 4. It will be observed that this latch mechanism may be used independently of any locking mechanism. The drawings show the latch in connection with the locking mechanism described in my Patent No. 860,055, dated July 16, 1907.

Having now explained my improvements, what I claim as my invention and desire to secure by Letters Patent, is—

1. In a lock, the combination of a case, a latch bolt mounted therein and having an enlarged rear end provided with inclined cam faces and lateral depressions, a lever mounted in the case and having one end pivoted in one 105 of the depressions, the other end of the lever being weighted, and tending to hold the latch 110
